United States Patent Office

Des. 216,651
Patented Feb. 24, 1970

216,651

IMPRINTER

William Plumb Barbour, Fairfax County, Va., assignor to
Farrington Business Machines Corporation, Springfield,
Va., a corporation of Massachusetts

Filed Jan. 31, 1968, Ser. No. 10,374

Term of patent 14 years

Int. Cl. D18—02

U.S. Cl. D64—11

Fig. 1

*Fig. 2**Fig. 3*FIGURE 1 is a front perspective view of an imprinter showing my new design.

FIGURE 2 is a back perspective view thereof.

FIGURE 3 is a side elevation view thereof.

The essential features of the design reside in the portions shown in solid lines on the drawing, conventional numerals being shown in broken lines in FIGURE 1.

I claim:

The ornamental design for an imprinter, as shown and described.
